UNITED STATES PATENT OFFICE.

CHARLES A. JUENGST, OF CROTON FALLS, NEW YORK.

METHOD OF SEWING SIGNATURES TO FORM BOOKS.

No. 893,513.

Specification of Letters Patent.

Patented July 14, 1908.

Application filed February 24, 1908. Serial No. 417,800.

To all whom it may concern:

Be it known that I, CHARLES A. JUENGST, a citizen of the United States, residing at Croton Falls, in the county of Westchester 5 and State of New York, have invented an Improvement in the Methods of Sewing Signatures to Form Books, of which the following is a specification.

My invention relates to an improved 10 method of sewing signatures to form books, with the object of simplifying the construction, enabling the said book to be laid out substantially flat and at the same time locking firmly together the loops of thread that 15 are pushed out of the back fold.

In carrying out my invention, I lay a thread along, through and within the back fold of each signature and about the same time push out of the back fold several loops 20 of each thread. After the threads of all the signatures collated have been thus laid through and the loops pushed out of the back fold, one or more of these loops as may be desired, is pulled through other aligned 25 loops of the signatures and the remaining threads are drawn upon to draw down the loops and thus hold the signatures together; the threads of the loops that have been drawn 30 through, forming, as it were, a flexible bar connecting or tying together the respective signatures.

In the drawing, Figures 1, 2 and 3 are perspective views showing a number of collated signatures and showing forms of the method 35 employed by me in connecting the same. Figs. 4, 5 and 6 are diagrammatic views of the sewing threads, Fig. 4 showing the threads of Fig. 1,—Fig. 5 the threads of Fig. 2 and Fig. 6 the threads of Fig. 3. Fig. 7 is a 40 longitudinal section illustrating that any one of these forms of sewing may be employed with the signatures where the back fold is cut away to leave a groove. Figs. 8 and 9 are detached longitudinal sections each showing 45 a loop of thread pushed out of the back fold; Fig. 8 having two threads in the grip of the loop and Fig. 9 showing four threads in the grip of the loop, as will be the case in Figs. 1 and 3 with reference to Fig. 8, or Fig. 50 2 with reference to Fig. 9.

Referring particularly to Figs. 1, 2 and 3, *a b c d e f* and *g* illustrate groups of seven collated signatures, along, through and within the back fold of each of which is laid the 55 threads *2 3 4 5 6 7 8*. These threads are laid along, through and within these back folds

by any suitable devices and other suitable devices are employed for pushing parts of these threads out through the back fold of each signature leaving loops projecting. 60 These loops are preferably at corresponding places in the backs of the signatures and in line when the signatures are brought together as shown in the drawing.

In the form of method shown in Figs. 1 and 65 4, the loops of the thread *2* from the signature *a* have been engaged by a suitable device passing through all of the other loops in line and these loops have been pulled out and through all of the other loops in line so that 70 the free end of each of these loops extends beyond the loops of the thread *8*, projecting from the signature *g*. The loops of all intermediate threads are then drawn down tight as illustrated in Fig. 8. The doubled 75 thread of the loops of the thread *2* therefore forms a flexible connecting member for all the signatures from *a* to *g* inclusive that are collated and illustrated in Fig. 1; the sewing threads being shown in Fig. 4 in 80 the diagrammatic view. Fig. 2 illustrates a form of this method of sewing the signatures of the book, and Fig. 5 shows diagrammatically the sewing threads, and according to this form the projecting loops of each thread 85 laid along through and within the back fold of each signature are connected by first drawing the loops of the thread *2* of the signature *a* through all of the other loops in line and then in the opposite direction drawing 90 the loops of the thread *8* of the signature *g* through all of the other loops, thus leaving in all of the intermediate loops four threads which form a flexible medium for firmly connecting the signatures together, the said intermediate loops being drawn down as tight 95 as possible around the four threads as shown in Fig. 9; Fig. 5 showing these threads diagrammatically.

A further form of my invention is shown in 100 Figs. 3 and 6, in which the four loops of the thread *5* of the signature *d* are engaged by suitable devices and pulled through the loops of the other signatures in opposite directions, that is to say, beginning at the left hand the 105 first of these loops is in one direction pulled through the loops of the signatures *e f g*; the second loop of the signature *d* is pulled through the loops of the threads of the signatures *c b* and *a* in the opposite direction; the third loop 110 of the signature *d* is pulled through the loops of the signatures *e f* and *g* similar to the first

loop, and the fourth loop of this signature *d* is in the opposite direction pulled through the loops of the signatures *c b* and *a* as was the second loop; thus the four loops of the 5 central signature thread are employed in connecting all of the signatures together and when the threads 2 3 4 6 7 and 8 are pulled down they engage and grip the doubled thread of the loops of the thread 5 of the signature *d* as diagrammatically shown in Fig. 6 and as also equally well shown in Fig. 8. Fig. 7 simply serves to illustrate that instead of holes being formed by a puncturing instrument in the back fold of each signature, that these back folds may be cut through by removing the sections as is old in this art and the loops of the threads be laid through these cuts; said cuts leaving ample space for the respective threads as especially 10 illustrated in Figs. 4, 5 and 6, for it will be apparent that as shown in Figs. 4 and 6, there would be in such cuts or channels four threads, or six threads according to the diagrammatic view of Fig. 5, and the special 15 illustration of Fig. 7. The free ends of the respective threads that are laid through and within the back folds of the signatures may be trimmed off in trimming the signatures for binding or they may be fastened in the fold 20 or over the back of a signature or in any other desired manner which forms no part of my present invention; this method of sewing signatures to form books having particular reference to the cheaper form of books or 25 those inexpensively made.

I claim as my invention:

1. The method herein specified of sewing signatures to form books, the same consisting in laying a thread along, through and 30 within the back fold of each signature in succession, forming loops of each thread in suc-

cession that are passed out through the back fold of the signatures, then engaging the loops of one of the signatures and drawing the same through the similar aligned loops of other signatures and then drawing down the remaining loops of thread around the aforesaid threads to hold the signatures together in forming a book. 45

2. The method herein specified of sewing signatures to form books, the same consisting in laying a thread along, through and within the back fold of each signature in succession, forming loops of each thread in succession that are passed out through the back fold of the signatures and then drawing the several loops of an outside signature through all of the loops of the other signatures and then drawing down the loops of said other signatures around the threads of the loops 55 drawn from the outside signature so as to connect the signatures in forming a book. 60

3. The method herein specified of sewing signatures to form books, the same consisting in laying a thread along, through and 65 within the back fold of each signature in succession, forming loops of each thread in succession that are passed out through the back fold of the signatures and then engaging the respective loops of both outside signatures 70 and drawing the same in opposite directions through the aligned loops of the intervening signatures and then drawing down the threads of the intervening signatures around the thread so drawn through to connect the 75 signatures and form the book.

Signed by me this 28th day of January 1908.

CHAS. A. JUENGST.
